UNITED STATES PATENT OFFICE.

MICHAEL J. ROCHE, OF NEWTON CENTER, MASSACHUSETTS.

SAFETY ATTACHMENT FOR PRESSES.

Application filed December 21, 1925. Serial No. 76,714.

This invention relates to a safety attachment for presses, and particularly to a safety attachment of that type in which the safety factor is secured by making it necessary that 5 the operator should have both hands engaged when the press is tripped thus obviating the possibility of his being able to place his hand in the danger zone at this time.

In my present invention I provide the press 10 with the usual one-revolution clutch and I provide a novel means for tripping the clutch which requires the use of both hands for its operation. In order, therefore, to trip the clutch the operator has to use both hands 15 which makes it impossible for him to have either hand in the danger zone when the press is operated.

In order to give an understanding of the invention I have illustrated in the drawings a 20 selected embodiment thereof which will now be described after which the novel features will be pointed out in the appended claims.

Fig. 1 is a side view of a press having my invention applied thereto;

25 Fig. 2 is a section on the line 2—2, Fig. 1;

Fig. 3 is a fragmentary perspective view illustrating the clutch-tripping mechanism;

Fig. 4 is a section on the line 4—4, Fig. 1;

Fig. 5 is a detail of the clutch actuator.

30 In the drawings 1 indicates generally a punch press which may be of any usual construction and which is provided with the bed 2 and the plunger 3 which carries the die. The plunger is guided in a guideway 4 and 35 is operated by means of the usual eccentric 5 on the driving shaft 6. The shaft is actuated from a pulley 7 which is operatively connected to the shaft through a clutch device indicated generally at 8 and which may be of 40 any usual or suitable construction. This clutch device is of the ordinary one-revolution type and it is controlled by a controlling dog 9 which is pivoted to the press at 10. This type of clutch is one which is very 45 familiar and hence I have not thought it necessary to illustrate it herein. It is sufficient to say that when the controlling dog 9 is swung downwardly into the position shown in Fig. 5 the clutch will be automatically engaged 50 and when the dog is in its operative position shown in full lines Fig. 3 it will operate to disengage the clutch after the completion of one revolution.

55 My invention relates to a novel two-hand mechanism (that is a mechanism which requires the use of both hands to operate it)

for tripping the clutch, said mechanism being so constructed that after the clutch is tripped it will make but one revolution and will then be automatically disengaged so that 60 in order to trip it again it is necessary to again manipulate the two-hand mechanism. This will prevent the possibility of a repeat.

The clutch is tripped by means of a sliding actuator 11 which is mounted for sliding 65 movement in a bracket 12 carried by the press frame and which requires for its operation the use of both hands as will be presently described. This slide 11 has a lug 13 on its upper side which co-operates with a latch 14 that is pivoted to the clutch dog 9. Said dog has rigid therewith a depending arm 15 from which extends a pin or projection 16 against which the latch 14 rests. The projection 16 limits the swinging movement of the latch in one direction, while permitting its free movement in the opposite direction. When the parts are in the position shown in Fig. 3 the latch 14 is situated between the projection 16 and the lug 13. With 70 the parts in this position a movement of the slide 11 to the left will operate through the lug 13 and latch 14 to swing the clutch dog 9 downwardly as shown in dotted lines Fig. 3 and in full lines Fig. 5, which will permit the 75 clutch to be thrown into engagement.

The mechanism for operating the clutch actuator 11 is such as to cause the slide to move into the dotted line position Fig. 5 in which position the projection 13 has wiped 80 past the end of the latch 14 thus releasing the clutch dog and allowing it to assume its normal position shown in full lines Fig. 3 under the influence of a spring 17.

The clutch dog 9 will thus cause a disengagement of the clutch after it has made one revolution and the clutch can only be tripped again by returning the slide 11 to the full line position Fig. 3 and then moving it again toward the left. During the return movement of the slide to the full line position Fig. 3 the projection 13 will wipe under the latch 14, the latter swinging away from the stud 16 to permit this operation.

As stated above the actuating slide 11 is 105 operated by a two-hand mechanism which requires the use of both of the operator's hands to manipulate it.

Said slide 11 is connected by means of a link 18 to an arm 19 fast on a vertical shaft 20 110 which is journalled in suitable bearings 21 carried by the press. Rocking movement of

the shaft 20, therefore, will operate to give the slide 11 its sliding movement.

To operate the shaft 20 I have provided the following mechanism. Pivoted to the press at each side thereof is a lever, said levers being indicated at 22 and 23 respectively. These levers are pivoted at 24 to brackets 25 on the side of the press. These levers extend forwardly to the front of the press and are provided with handles 26 by which they may be operated. The two levers are connected to the shaft 20, the lever 23 being connected to an arm 27 fast on the shaft 20 and the lever 22 being connected to a link 28 which in turn is connected to another arm 29 fast on the shaft 20. The connection between the lever 23 and the arm 27 is a pin-and-slot connection to prevent binding of the parts.

Each lever has associated therewith a locking device which normally locks it in the position shown in full lines Fig. 4 and the locking devices are constructed so that they can only be released by the hands of the operator when he grasps the handle 26.

Each lever 22 has a locking latch 30 pivoted thereto at 31, these latches co-operating with teeth 32 on brackets 33 which are secured to the press at each side thereof. Each locking latch has a handle 34 rigid therewith and by which it may be manipulated to release it from the bracket 33.

The position of the levers 22, 23 shown in Fig. 4 corresponds to the position of the actuating slide 11 in Fig. 3 and in order to move the slide to the left Fig. 3 to disengage the clutch it is necessary to swing the levers 22 into the dotted line position Fig. 4. This can only be accomplished by releasing both locking latches 30.

The handles 34 are so positioned that when the operator grasps the handles 26 he also grasps the handles 34 and by pressing the handles 34 toward the handles 26 the spring-pressed locking latches 30 will be disengaged from the teeth 32. This will permit the operator to swing the levers 22 into the dotted line position Fig. 4 and thus turn the shaft 20 and move the clutch actuator 11 into the dotted line position shown in Fig. 5. During this movement the clutch is tripped as above described and as soon as the projection 13 has passed the nose of the latch 14 the clutch dog will return to its operative position.

In order to trip the clutch a second time it is necessary for the operator to return the levers 22, 23 to the full line position Fig. 4, which will return the slide 11 to its full line position Fig. 3 and then to swing the levers outwardly into the dotted line position again and this can only be done in case the operator has both hands engaged in manipulating the two levers.

With this device it is impossible for the

operator to have either of his hands in the danger zone at the time when the clutch is tripped and the press operated.

35 indicates springs connecting the levers 22, 23 to the press frame, these springs operating to return the levers 22, 23 to the full line position Fig. 4 automatically when the operator releases hold of the handles 26.

I have also provided herein a device for locking the plunger from downward movement which device is released by the swinging movement of the levers 22, 23. The plunger has secured to each side thereof a ratchet member 36 provided with teeth 37. These teeth co-operate with locking members 38 which are slidably mounted in boxes 39 secured to the press frame. Each of these locking members 38 is acted on by a spring 40 which tends to force it inwardly, each spring acting at one end against a collar 41 fast on the corresponding member 38 and at the other end acting against the end of the housing 39. The outer end of each locking member 38 is provided with a head 42 having a slot 43 therein in which is received a pin 44 carried by the corresponding lever.

When the parts are in the position shown in full lines Fig. 4 the levers 22, 23 are locked by the locking pawls 30 and the locking members 38 also lock the plunger from downward movement by their engagement with the teeth 37. When the levers 22, 23 are swung outwardly to trip the clutch said swinging movement will operate to withdraw the locking members 38 from locking engagement with the plunger thus unlocking the plunger.

It is the intention that the locking members 38 should lock the plunger in its raised position, which is the position the plunger occupies when the clutch is disengaged.

In order to prevent the pawl from being accidentally thrown into locking engagement with the teeth 37 after the clutch has been tripped and when the plunger is moving downwardly, an occurrence which would be likely to cause damage to the parts, I have provided guards 420 in the form of plates which overlie the upper teeth 37 of the rack. These guards will be so adjusted that they will cover all of the ratchet teeth above the one which is in engagement with the locking member 38 when the plunger is fully raised. If, therefore, after the clutch is tripped and the plunger starts its downward movement the locking members are accidentally moved inwardly they will engage the guard members 420 and will be prevented thereby from locking into the ratchet teeth. Hence this device will provide means for locking the plunger in its elevated position but will prevent the lock from becoming operative after the plunger starts downwardly.

The rack members 36 are preferably secured to the plunger so that they can be ad-

justed as necessary to cause the locking members 38 to function properly.

With my invention, therefore, it will not be possible for a person to place his hand in the danger zone while the press is operated because in order to operate the press the operator is required to use both hands to manipulate the levers 22, 23.

Furthermore, the construction has the advantage that a repeat is not possible since the operative connection between the actuator 11 and the clutch dog is disrupted after the clutch is disengaged and can only be reestablished by again returning the actuator 11 to the full line position shown in Fig. 3.

I claim:

1. In a safety device for presses operated by a one-revolution clutch, the combination with a clutch actuator having a two-and-fro movement, movement in one direction operating to trip the clutch, and means for operating the actuator comprising two levers and a lock for each lever which is released by grasping the lever, both of which locks must be released at the same time in order to permit the operation of the levers.

2. The combination with a press having a vertically-moving plunger, of a clutch for operating said plunger, two ratchet members connected to the plunger, a locking pawl cooperating with each plunger to lock the plunger against downward movement, two levers pivoted to the press, each lever being connected to one of the locking pawls, where-
35 by both levers must be actuated to unlock the

plunger, and a clutch-tripping member which is connected to and operated by both levers.

3. In a device of the class described, the combination with a spring-actuated clutch-controlling member adapted to control a one-revolution clutch pivoted to said controlling member and freely swingable in one direction, said controlling member having a stop to limit the swinging movement of the latch in the other direction, an actuator having a to-and-fro movement and provided with a projection adapted to engage the latch during the movement of the actuator in one direction and thereby swing the latch against the stop and thus operate the clutch-controlling member, said latch wiping over the projection during further movement of the actuator, thereby allowing the controlling member to return to operative position, said latch being swung away from the stop by the projection on the return movement of the actuator, and means to operate the actuator.

4. The combination with a press, of two levers pivoted thereto each having a handle, means connecting said levers whereby they operate in unison, a lock normally locking each lever from movement, each lock being adapted to be released by grasping the handle of the corresponding lever, and means actuated by said levers for controlling the operation of the clutch.

In testimony whereof, I have signed my name to this specification.

MICHAEL J. ROCHE.
